Patented Jan. 22, 1974

230,035

AUTOMATIC ANIMAL WATERING APPARATUS

Jay D. Bowman, 2271 Hillside, Norco, Calif. 91760

Filed Apr. 10, 1972, Ser. No. 242,892

Term of patent 14 years

Int. Cl. D30—03

U.S. Cl. D30—16

Fig. 1.

Fig. 2.

Fig. 3.

FIG. 1 is a front, top and right side perspective view of an automatic animal watering apparatus, showing my new design, a front, top and left side perspective view being substantially a mirror image thereof;

FIG. 2 is a rear elevational view; and

FIG. 3 is a cross-sectional view thereof taken on line 3—3 in FIG. 2.

I claim:

The ornamental design for an automatic animal watering apparatus, substantially as shown and described.
